DESIGN FOR A CASING FOR WASHING MACHINES

Application filed December 20, 1930. Serial No. 38,052. Term of patent 14 years.

To all whom it may concern:

Be it known that we, EARL S. BURDICK and CHARLES R. THOMSON, citizens of the United States, residing respectively, at Milwaukie, county of Clackamas, State of Oregon, and at Portland, county of Multnomah, State of Oregon, have invented a new, original, and ornamental Design for a Casing for Washing Machines, of which the following is a specification, reference being had to the ac-

companying drawings, forming part thereof. Figure 1 is a perspective view from the driving end of the machine. Figure 2 is a perspective view taken from a diagonally opposite corner from Figure 1.

We claim:

The ornamental design for a casing for washing machines, as shown.

EARL S. BURDICK.

CHARLES R. THOMSON.
